NICK RICH
INVENTOR
Victor J. Evans
ATTORNEY

Patented Nov. 21, 1922.

UNITED STATES PATENT OFFICE.

NICK RICH, OF HAILEYVILLE, OKLAHOMA.

PASSENGER REGISTER.

Application filed November 15, 1920. Serial No. 424,234.

To all whom it may concern:

Be it known that I, NICK RICH, a citizen of the United States, residing at Haileyville, in the county of Pittsburg and State 5 of Oklahoma, have invented new and useful Improvements in a Passenger Register, of which the following is a specification.

This invention relates to a register, and more particularly to a register to replace the 10 reminder tickets given passengers by railway conductors.

Quite frequently misunderstanding occurs on passenger trains, by the loss of these reminder tickets, and also by the failure of 15 the conductor to remember the particular station at which certain passengers desire to leave the train, and it is an object of this invention to provide a register which will eliminate the use of the usual pasteboard 20 tickets given to the passengers placed in the seat-back in front of them or slipped in men's hat bands, which register will eliminate any misunderstandings which might 25 arise from the loss of such tickets and which will provide an indicator which is clearly 30 visible from the aisle of the passenger cars to the conductor or other train man at what station the passenger in the seat desires to leave and also the number of passengers which desire to alight at such station.

More specifically, the invention comprehends the provision of a passenger register comprising a panel bearing a plurality of suitable indicia and carrying a rod upon 35 which indicators are mounted to designate certain of said indicia, which indicia in turn represents stations along the route of the train on which the registers are mounted and also may embody means for illuminating 40 the register whenever one of said indicators, which are detachable, is mounted on said rod.

Other objects of the invention will appear in the following detailed description taken 45 in connection with the accompanying drawing wherein:

Fig. 1 is a front elevation of the improved passenger register.

Fig. 2 is a front view of the register showing it open to permit the placing of indicators on the rod.

Fig. 3 is a detailed section taken on the line 3-3 of Fig. 2 and illustrates one of the indicators mounted upon the rod.

Fig. 4 is a detailed section on the line 55 4-4 of Fig. 2.

Fig. 5 is a front elevation, partly in section, of a modified form of the passenger register.

Fig. 6 is a cross section through the modified form of register taken on line 6-6 of Fig. 5.

Fig. 7 is a detailed section of the modified form of register taken on the line 7-7 of Fig. 5.

Fig. 8 is a diagrammatic view of the electric circuit in the modified form of register.

Referring more particularly to the drawings the improved passenger register comprises a casing 1 which is attached by suitable attaching means through the medium of the tabs 2, to the side of a passenger coach in close proximity to the seat, it being desirable to position one of the registers alongside of each seat in a passenger coach. 70 The casing 1 has its edge 3 horizontally connected at 4 to the main body thereof to permit access to the interior of the casing. A transparent panel 5 is mounted in the casing frame, and terminates short of the width 80 of the casing, its free edge adapted to be engaged by the inner free edge of the glass or transparent pane 6 which is carried by the horizontal edge 3. The transparent panels 5 and 6 may be attached to their respective parts of the casing in any suitable manner, such as by channel attaching members 7. The hinged edge 3 has its lower end folded inwardly as shown at 8 for engagement over the adjacent edge of the bottom 90 9 of the casing 1 and this folded edge 8 carries a staple 10 which is shaped to be inserted through a hasp 11 carried by the bottom 9 and to receive the shackle 12 of any suitable type of lock 13 therethrough for locking 95 the casing to prevent malicious tampering with the register.

A panel 14 is mounted in the casing 1 and is divided into a plurality of bosses 15 the uppermost of which bears the words "Station number" while the succeeding 10 spaces bear the numbers 1 to 0 inclusive. The space directly below the space which carries the 0 has the word "Passengers" printed thereon while the space directly below this 105 space bears the numbers 1 to 4 inclusive.

A rod 16 is carried by the casing 1 being attached thereto in any suitable manner and it is adapted to support indicators 17 which are removably mounted thereon, and may be 110 spaced at any position along the rod to indicate the desired number of station at which

the passenger in the seat at which the register is mounted desires to leave the train. The indicators 11 are placed on the rod by the conductor and are held securely in place 5 against dislodgment by movement or vibration of the train, by set screws 18. In use, indicators 17 are placed on the rod 16 to indicate the number of the station and number of passengers, for example, if two passengers desire to leave the train at station number 350, the conductor places the indicators 17 on the rod 16 to indicate the spaces 3, 5 and 0 and an indicator to indicate the space 2 below the title "Passengers." The indicators 17 are preferably in a plurality of colors such as red, white and blue, the colors of the flag of the United States of America, the sequence of which is well known to every one, thus in placing the indicators 17, the conductor will place the red indicator at space 3, the white indicator at space 5 and the blue indicator at space 0, and thus can tell by a glance that there are two passengers to leave the train at station number 350. Black indicators may be provided for use when it is necessary to use four of them to indicate the number of the station.

As it is sometimes quite dark in passenger coaches it might be difficult for the conductor 30 to readily read the register and, therefore, it may be desirable to coat the indicators and numbers on the panel 14 with a phosphorous paint so that they will glow in the dark, however, a modified form of the invention is 35 illustrated in Figs. 5 to 8 of the drawing inclusive, wherein an electric incandescent lamp 30 is provided to illuminate the panel 14'. The modified form of the invention comprises a casing 1' similar in construction 40 to the casing 1 having its edge 3' hinged thereto in the same manner as the edge 3 and is connected to the casing 1. However the casing 1' is preferably deeper within the casing edge to provide a space for receiving 45 a battery 31 from which the electric current is supplied to energize the lamp 30. The battery 31 may be of any approved conventional type and it has one of its terminals connected to the lamp 30 as shown in the circuit diagram as shown in Fig. 8, while its 50 other terminal is connected to the panel 14'. The panel 14' is supported within the casing by supports 32 of insulating material so as to completely insulate the panel 14' from the casing 1'. The lamp 30 has its terminal 33 opposite the terminal to which the battery 31 is connected and connected by suitable contacting wire 34 to a spring clip 35 which is removably mounted upon the rod

16'. The ends of the rod 16' are threaded or otherwise suitably mounted in the collars 36 of insulation carried by the top and bottom of the casing 1 to insulate the rod from the casing. The indicators 17' are constructed of metal, and when mounted upon the rod 60 16' engage against the panel 14' closing the electric circuit through the battery 31, the panel 14', rod 16', wire 34, lamp 30 and back to the battery 31 thus energizing the lamp 30. However, should it be desired 65 to use the modified form of indicator structure without causing energizing of the lamp 30 when an indicator 17' is mounted upon the rod 16' the spring clip 35 may be removed from the rod 16' thus forming a 70 break in the circuit. A suitable supporting bracket 37 is provided for supporting the wire 34 to prevent the spring clip 35 from falling downwardly in the casing 1' out of reach of the operator of the register. 75

It is, of course, to be understood that the invention may be constructed in various other manners and the parts associated in other relations and, therefore I do not desire to be limited in any manner except as set forth in the claims hereunto appended. 80

Having thus described my invention what I claim is:

1. In a passenger register, a casing, a central partition therein and having indicia 90 thereon, a rod extending longitudinally in said casing in proximity to said partition, indicators adapted to be removably mounted upon said rod, said casing having one side edge hingedly supported at one end, a front 95 transparent side for said casing formed of a rigid section and a movable section, said movable section being carried by said hinged edge, said rigid and movable transparent sections engaging in edgewise relation. 100

2. In a passenger register, a casing, a central partition therein and having indicia 105 thereon, a rod extending longitudinally in said casing in proximity to said partition, indicators adapted to be removably mounted upon said rod, said casing having one side edge hingedly supported at one end, a front transparent side for said casing formed of a rigid section and a movable section, said movable section being carried by said hinged 110 edge, said rigid and movable transparent sections engaging in edgewise relation, said hinged edge having a transverse extension on its lower end equal in width to the width of the transparent movable section and adapted 115 to engage beneath the bottom of said casing.

In testimony whereof I affix my signature.
NICK RICH,
